UNITED STATES PATENT OFFICE.

IRA H. LONG, OF PERU, INDIANA.

FOLDING UMBRELLA.

1,071,762.

Specification of Letters Patent. Patented Sept. 2, 1913.

Application filed December 5, 1912. Serial No. 735,131.

To all whom it may concern:

Be it known that I, IRA H. LONG, a citizen of the United States, residing at Peru, in the county of Miami and State of Indiana, 5 have invented certain new and useful Improvements in Folding Umbrellas; and I do declare the following to be a full, clear, and exact description of the invention, such as will enable others skilled in the art to which 10 it appertains to make and use the same.

This invention relates to improvements in folding umbrellas.

One object of the invention is to provide a folding umbrella having an improved construction and arrangement of telescoping ribs.

Another object is to provide a folding umbrella which will be simple, strong, durable and inexpensive in construction, reliable in use and which may be quickly and easily folded and unfolded.

With these and other objects in view the invention consists of certain novel features of construction, and the combination and 25 arrangement of parts as will be more fully described and claimed.

In the accompanying drawings: Figure 1 is a central vertical section of my umbrella with the parts arranged in position and 30 opened for use; Fig. 2 is a side view partly in section showing the position of the parts when the umbrella is closed; Fig. 3 is a similar view showing the position of the parts when the umbrella is closed and folded 35 and the sections of the handle disconnected; Fig. 4 is an enlarged longitudinal sectional view through the outer end of one of the inner members of the ribs and the adjacent end of one of the braces illustrating the 40 outer member of the rib in a projected or operative position; Fig. 5 is a cross sectional view through the upper portion of the umbrella staff or handle taken on the line 5—5 of Fig. 1 and looking upwardly; Fig. 6 is 45 a similar view taken on the line 6—6 of Fig. 1 looking downwardly; Fig. 7 is a similar view taken on the line 7—7 of Fig. 1; Fig. 8 is a detail perspective view of one of the braces; Fig. 9 is a top plan of one of the 50 inner tubular members of the ribs showing more particularly the manner in which the guide slot for the locking lug of the outer member of the rib is constructed; Fig. 55 10 is a detail perspective view of one of the outer members of the ribs.

In the embodiment of the invention I

provide a collapsible rod or staff comprising an outer tubular section 1, an intermediate tubular section 2 and an inner section or handle 3. The outer tubular section 1 of the 60 staff is threaded interiorly in its outer and inner ends, while the intermediate section 2 has on its inner end a reduced exteriorly threaded stud 4 which is adapted to be screwed into the threaded inner end of the 65 outer section 1. The section 2 has its outer end interiorly threaded and into said threaded end of the section 2 is adapted to be screwed a reduced threaded stud 5 on the 70 inner end of the handle section 3 of the staff. By constructing the staff and handle in the manner described it will be seen that the sections thereof may be readily disconnected and collapsed when the umbrella is folded, and readily assembled when the umbrella is extended and opened for use. 75

In the threaded outer end of the outer section 1 of the staff is secured a tip or point 6 having a reduced threaded shank 7 which is adapted to be screwed into the 80 threaded outer end of the section 1. On the shank 7 of the tip is secured a clamping ring 8 whereby the inner edges of the covering 9 of the umbrella is secured to the tip between the ring and the enlarged inner end of the tip as clearly shown in Fig. 1 of the drawing. The handle section 3 of the staff 85 may be provided with any form of head or constructed in any desired shape.

The outer end of the tubular outer section 1 of the handle carries the "notch" which consists of an annular series of radially projecting ears or lugs 10 to which are pivotally and detachably connected the inner ends of the ribs of the umbrella. The 95 lugs 10 are preferably formed by slitting the end of the section 1 inwardly for a suitable distance and then bending the slitted parts of the metal outwardly at substantially right angles to the staff. The ends of the lugs when thus formed are bent or turned inwardly to form eyes 11 adapted to receive a rib fastening wire 12 which is inserted therethrough and through the inner ends of the ribs as will be hereinafter 105 more fully described.

The ribs of the umbrella comprise inner tubular members 13 on the outer ends of which are formed pairs of apertured ears 14 between which are engaged the eyes 11 on 110 the ends of the lugs 10 of the notch and with which is engaged the fastening wire 12

whereby said inner members of the ribs are detachably secured to the staff. In the upper sides of the members 13 are formed longitudinal slots 15 which gradually decrease in width from the outer toward the inner 5 ends of the members and which open through said outer ends as shown. At or near the inner end of each of the members 13 and communicating with the narrow end of the slot 15 is an offset rectangular notch 16 the combined width of which and the width of the adjacent end of the slot is substantially the same as the width of the wider outer portion of the slot as is clearly shown in 10 Fig. 9 of the drawings. On the lower side of the inner ends of the members 13 are formed transverse brace receiving eyes or loops 17, said eyes or loops being preferably formed from a reduced extension of the inner end of the members 13 as shown. 15

20 Slidably mounted in the inner members 13 of the ribs are outer rib members 18 each of which preferably comprises an enlarged cylindrical head or inner end 19 which is of suitable length and has a diameter substantially the same as the inside diameter of the tubular inner members of the ribs and has its outer portion preferably in the form of a flat spring metal rod 20, the outer end of which is reduced and has formed thereon a 25 knob 21. To the reduced ends of the outer rib members are secured in the usual manner the outer edges of the covering 9 of the umbrella. On the outer sides of the heads 30 19 of the outer rib members at the outer ends of said heads are formed outwardly projecting guiding and locking lugs 22 which correspond in width to the wider part of the slots 15 in the inner members of the ribs and with which said lugs are slidably 35 engaged. The outer ends of the lugs are preferably provided with offset heads 23 which engage the outer surface of the rib members 13 adjacent to one side of the slots 40 15 therein. By providing the lugs 22 it will be seen that when the outer members of the ribs are drawn outwardly to operative positions in the tubular inner members of the ribs the lugs 22 will gradually spring apart 45 15 the edges of the slotted portion of the members 13 or in other words will open said slots to the width of the lugs until the latter are brought opposite to the notches 16 at the outer ends of the slots whereupon the edges 50 55 of the slotted portion of the rib members will again spring together and engage the notches 16 with said lugs, thus locking the outer members of the ribs 18 in their projected or operative positions. When it is desired to again retract the outer rib members or to push the same back into the inner members it is simply necessary to grasp the outer ends of said outer rib members and to turn or twist the same slightly, thus causing 60 65 the lugs 22 to spring the edges of the slots

apart to a sufficient extent to disengage the lugs from the notches 16 whereupon the outer sections 18 of the ribs may be pushed back into the tubular inner members as shown in Fig. 3 of the drawings.

70 Slidably mounted on the outer section 1 of the staff is a runner 24 having secured to its outer side a spring catch 25 on the inner end of which is an inwardly projecting stud 26. The stud 26 works through an aperture 27 in one side of the runner and is adapted to spring into engagement with inner and outer locking apertures 28 and 29 in the outer section 1 of the staff whereby the runner is locked in position for holding the ribs 80 of the umbrella in an operative and in an inoperative or folded position. On the outer end of the runner are formed a series of brace attaching eyes 30 said eyes being preferably formed by slitting the inner end of 85 the runner for a suitable distance and bending or turning the slitted portions of the metal outwardly as shown. With the eyes 30 is engaged a brace fastening wire 31 by means of which the inner ends of the braces 90 32 of the umbrella are detachably and pivotally secured to the runner.

95 The braces 32 are preferably formed from narrow strips of sheet metal which are bent or folded longitudinally and flattened or pressed together at the inner portion of the braces. The inner end of the folded part of the brace is slitted inwardly for a suitable distance along the fold to form attaching lugs 33 which are bent outwardly and spaced 100 apart to the width of the eyes 30 on the end of the runner and with which said lugs 33 are engaged. In the ends of the lugs 33 are formed alined apertures 34 with which the fastening wire 31 of the braces is engaged 105 when passed through the eyes 30 thereby pivotally securing the inner ends of the braces to the runner. Secured to the outer ends of the braces are outer attaching loops 35 which are preferably formed of wire and 110 have their inner ends clenched and rigidly secured between the folded outer ends of the braces. The loops 35 are adapted to be engaged with the eyes 17 formed on the inner sides of the inner ends of the members 13 of the ribs whereby said braces are pivotally or loosely connected at their outer ends with the ribs to support the latter in an open or operative position.

115 By constructing an umbrella in accordance with my invention it will be seen that in order to fold or collapse the same it is simply necessary to lift the inner end of the spring latch 25 a sufficient distance to disengage the stud 26 thereof from the locking 120 aperture 28 in the outer section 1 of the staff and to push the runner 24 outwardly to the outer end of said staff member 1 in which position the runner will be held by the automatic engagement of the stud 26 of 125 130

the latch with the outer locking aperture 29 in the staff section 1. In thus moving the runner outwardly the inner ends of the braces are also carried outwardly thereby 5 permitting the ribs to be closed or folded inwardly against the staff. After the umbrella has thus been closed the lugs 22 on the inner ends of the outer members of the ribs are disengaged from the notches 16 in 10 the inner members in the manner described and said outer members of the ribs pushed back into the tubular inner members, thus reducing the ribs to half their full length. After these parts of the umbrella have been 15 thus folded and collapsed the outer and intermediate sections of the staff are disconnected and detached from the outer member or section 1 which as will be seen is of substantially the length of the collapsible or 20 telescoped ribs so that the entire umbrella is now reduced or shortened to a length corresponding substantially with the length of the inner members of the ribs. If desired the length of the folded umbrella may be 25 further shortened by disengaging the tip 6 from the outer end of the staff. It will be noted that the construction and arrangement of the various folding or telescoping parts of the umbrella is such that these parts 30 may be readily released and moved to inoperative and operative positions when desired.

From the foregoing description taken in connection with the accompanying drawings, the construction and operation of the invention will be readily understood without requiring a more extended explanation.

Various changes in the form, proportion and the minor details of construction may 40 be resorted to without departing from the principle or sacrificing any of the advantages of the invention as claimed.

Having thus described my invention, what I claim is:

1. In a folding umbrella, the combination 45 with a collapsible staff having a notch, a runner, and the braces pivotally connected at their inner ends with said runner; of telescopic ribs each composed of a tubular inner member and an outer member, the 50 former pivoted at its inner end to said notch and at its outer end to one of said braces and having a longitudinal slot in its wall tapering toward its outer end, and the outer member having a head movably mounted 55 in said inner member and provided with a lug projecting through said slot.

2. A telescopic umbrella rib comprising an inner member having a substantially tubular body with a longitudinal slot growing 60 narrower toward its outer end and there provided with a notch in one side, and an outer member slidably mounted within said inner member and having a laterally projecting lug of a width to fit the wider portion 65 of said slot and to spread apart the walls of the same as it is drawn outward.

3. The herein described telescopic umbrella rib comprising an inner substantially tubular member having a longitudinal slot 70 growing narrower toward its outer end and there provided with a lateral notch so that the width at the outer end of the slot and notch is the same as the width of the inner end of the slot; and an outer member having 75 an enlarged and rounded head at its inner end slidably fitting within said inner member and provided with a lateral lug of the same width as the inner end of said slot, and a head at the outer end of said lug. 80

In testimony whereof I have hereunto set my hand in presence of two subscribing witnesses.
